9

invention, reference being had for this purpose to the appended claims.

What is claimed is:

1. In an electrical musical instrument including a source of tone frequency current and a tone producing means, control means comprising a tube having a grid connected to said source, means to supply a substantially constant negative bias to the grid sufficient to bias the tube past cut off, a source of positive direct current, a keying switch for connecting the source to the grid, a resistor in series with the switch, a condenser in shunt with the resistor, and a shunt circuit around the resistor having a switch therein to vary the attack of the tone produced.

2. In an electrical musical instrument including a source of tone frequency current and a tone producing means, control means comprising a tube having a grid connected to said source, means to supply a substantially constant negative bias to the grid sufficient to bias the tube past cut off, a source of positive direct current, a keying switch for connecting the source to the grid, a resistor in series with the switch, a condenser in shunt with the resistor, a second condenser connected between the source and the resistor to ground, and a switch in series with the second condenser to vary the decay of the tone produced.

3. In an electrical musical instrument including a source of tone frequency current and a tone producing means, control means comprising a tube having a grid connected to said source, means to supply a substantially constant negative bias to the grid sufficient to bias the tube past cut off, a source of positive direct current, a keying switch for connecting the source to the grid, a resistor in series with the switch, a condenser in shunt with the resistor, a second condenser connected between the source and the resistor to ground, a shunt circuit including a switch around the resistor to vary the attack of the tone produced, and a switch in circuit with the second condenser to vary the decay of the tone.

4. In an electrical musical instrument including a source of tone frequency current and a tone producing means, control means comprising a tube having a grid connected to said source, means to supply a substantially constant negative bias to the grid sufficient to bias the tube past cut off, a source of positive direct current, a keying switch for connecting the source to the grid, a resistor in series with the switch, a condenser in shunt with the resistor, a second condenser connected between the source and the resistor to ground, a second resistor in series with the second condenser, a shunt circuit including a switch around the second resistor, and a switch in series with the second condenser.

5. An electrical musical instrument comprising an oscillator circuit including an electron discharge tube having a plate circuit and a cathode circuit, the plate and cathode circuits providing tone frequency currents of different character, a pair of control tubes having control grids connected respectively to the plate and cathode circuits of the oscillator, means to supply a substantially constant negative bias to the grids of the control tubes, and keying means for each of the control tubes including a plurality of switches in parallel for connecting the tube grid to separate sources of positive potential, and resistors between the switches and the sources to prevent cross feeding between the switch circuits when a

10

plurality of the switches are closed simultaneously.

6. In an electrical musical instrument including a plurality of sources of tone frequency current of different frequencies and tone producing means, control means comprising a plurality of control tubes connected to the sources respectively to control connection thereof to the tone producing means, and a plurality of keying means each including a plurality of switches connected to different ones of the control tubes, there being a plurality of switches associated with different keying means connected to each of the control tubes, resistors in series with the switches, condensers in parallel with the resistors, and shunt switches around the resistors to control the attack of a tone.

7. In an electrical musical instrument including a plurality of sources of tone frequency current of different frequencies and tone producing means, control means comprising a plurality of control tubes connected to the sources respectively to control connection thereof to the tone producing means, a plurality of keying means each including a plurality of switches connected to different ones of the control tubes, there being a plurality of switches associated with different keying means connected to each of the control tubes, resistors in series with the switches, condensers in parallel with the resistors, a second set of condensers connected respectively from points ahead of the resistors to ground, and switches in circuit with the condensers of the second set to control the decay of a tone.

8. An electrical musical instrument comprising sources of tone frequency currents of different characters and of the same fundamental frequency, a control tube connected to each of the sources to control the transmitted amplitude thereof, means for combining the outputs of the control tubes, and translating means connected to the last named means for translating the combined outputs into sound.

9. An electrical musical instrument comprising a plurality of sources of tone currents of different frequency of one character, a plurality of sources of tone currents of different frequency of a different character, keying means to control the transmission of signal currents from said sources, means for combining the tone currents of said one character, means for combining the tone currents of said different character, means for combining the outputs of the two last named means, and translating means for translating the combined outputs of the last named means into sound.

10. An electrical musical instrument comprising a plurality of sources of tone currents of different frequency of one character, a plurality of sources of tone currents of different frequency of a different character, keying means to control the transmission of signal currents from said sources, a low impedance transformer for combining the tone currents of said one character, a low impedance transformer for combining the tone currents of said different frequency, and translating means connected to both of the transformers to translate the combined outputs thereof into sound.

11. An electrical musical instrument comprising a plurality of oscillator circuits each including an electron discharge tube having a plate circuit and a cathode circuit, control tubes associated with the plate and cathode circuits of the oscillators respectively, means for combining

ROTARY DRIVE WHEEL TYPE CAN OPENER

Robert E. McLean, Fort Benning, Ga.

Application May 28, 1946, Serial No. 672,849

9 Claims. (Cl. 30—9)

1

This invention relates generally to the class of cutlery and pertains particularly to improvements in can openers of the rotary drive wheel type.

An object of the present invention is to provide a can opener of the character stated which is designed to be held in one hand while the other hand is employed for operating a rotary drive wheel and wherein the said rotary drive wheel and cutter are relatively movable and are forced together by the hand holding the device, through the medium of a fixed and a movable handle.

A further and more specific object of the invention is to provide a can opener of the rotary drive wheel type wherein a novel arrangement is provided of a body plate carrying a fixed handle and a pivotally mounted handle by means of which the rotary drive wheel is shifted toward a cutter, the handles being disposed and formed in a novel manner whereby an accurate alignment is maintained at all times between the handles so that the device can be held and manipulated without having twisting strains applied thereto which might tend to throw parts out of alignment or which would impose a strain upon the hand gripping the handle.

Another object of the invention is to provide a rotary drive wheel type can opener of the unmounted type, having a pair of handles, one of which is rigidly fixed to a body plate while the other is pivotally coupled thereto for movement relative to the fixed handle and for effecting the penetration of a cutter element through a can head and also for maintaining desired traction between the drive wheel and the rim of the can to which the cutter is fixed.

A still further object of the invention is to provide in a can opener of the character stated a novel construction and mounting of a head rest for the can, by means of which desired down pressure is maintained for assisting in the maintenance of the stated traction between the driving wheel and the can rim.

The invention will be best understood from a consideration of the following detailed description taken in connection with the accompanying drawings forming a part of the specification, with the understanding, however, that the invention is not confined to a strict conformity with the showing of the drawings but may be changed or modified so long as such changes or modifications mark no material departure from the salient features of the invention as expressed in the appended claims.

In the drawings:

Figure 1 is a view in elevation of the outer or right-hand side of one embodiment of a can opener constructed in accordance with the present invention;

5 Figure 2 is a view in top plan of the same;

Figure 3 is a view in elevation of the left-hand or inner side of the said one embodiment;

Figure 4 is a view in side elevation of the outer or right-hand side of a second embodiment;

10 Figure 5 is a view in top plan of the second embodiment;

Figure 6 is a view in elevation of the outer or right-hand side of a third embodiment;

Figure 7 is a view in top plan of the third embodiment;

15 Figure 8 is a view in elevation of the inner or left-hand side of the third embodiment;

Figure 9 is a view in elevation of the forward end of the first embodiment shown in Figures 1-3

20 inclusive;

Figure 10 is a vertical section taken on the line 10—10 of Figure 6;

Figure 11 is a vertical section taken on the line 11—11 of Figure 1;

25 Figure 12 is a vertical section taken on the line 12—12 of Figure 1.

Referring now more particularly to the drawings, there is shown in Figure 1, in connection with the first embodiment of the invention, a body plate which is generally designated 10 and which, as shown, is substantially rectangular in outline and is vertically disposed when in use. This body plate, as clearly shown in Figures 9 and 11, comprises a lower portion *a* and an upper portion *b*.

30 The upper portion *b* is disposed at an oblique angle to the lower portion *a* and when the opener is held in position for use with the lower portion *a* vertical, the upper portion *b* will be inclined to the left or inwardly.

35 In the portion *a* of the body plate there is formed a vertically extending elliptical opening 11 and above this opening in the portion *b* is an opening 12, the purpose of which will be hereinafter described.

40 Below the opening 11 the body plate has formed integrally therewith and extending inwardly or to the left the can rest foot 13 against which the side of a can bears when the device is mounted thereon.

45 Numerals 14 generally designate a fixed handle, by which is meant a handle which is fixed to the body plate and against movement with respect thereto. This handle comprises the outer end portion 14a and the inner end portion 14b. The

inner end portion 14b is torsionally twisted with respect to the portion 14a and is positioned on the outer or upper side of the inclined portion b of the body plate to which it is secured by the rivets 15. The twist of the portion 14b is such that when it is secured to the body plate in the manner shown, the outer end portion which engages the hand, will be disposed in a vertical plane parallel with and passing across the inner side of the lower portion a.

The top edge of the portion 14a of the upper handle is shaped to provide the relatively wide flange 16, which is disposed in a plane extending across the underlying vertical portion of the handle as best seen in Figure 12.

The numeral 17 generally designates the lower handle which is movable relative to the body plate and to the handle 14 and this lower handle comprises the outer end portion 17a and the inner end portion 17b which extends across the inner side of the lower part a of the body plate as shown in Figures 3 and 11. The portion 17a of the lower handle is initially of materially greater length than the portion 14b of the upper handle and this longer part of the lower handle is bent back upon itself to form a yoke which is generally designated 18 and which comprises, in addition to the portion 17b, the rounded forward end part 18a and the outer plate portion 18b.

The lower part a of the body plate is received between the two portions 17b and 18b of the yoke and such portions extend across the elliptical opening 11 as is clearly shown in Figures 1, 3 and 11.

Passing through the forward end portion of the yoke, that is, through the two spaced parts thereof and also through the body plate 10, is a pivot pin or rivet 19 upon which the handle 17 rocks.

As shown in Figure 11 there is extended through the two sides of the yoke 18 a bearing sleeve 20 which has a portion threaded in the side plate 18b of the yoke as shown in Figure 11 and which has mounted thereon between the two side portions of the yoke, the spacer collar or ring 21. This spacer ring or collar lies in the elliptical opening 11 and is shiftable therein upon oscillation of the handle 17 and it functions to maintain the two sides of the yoke properly spaced so that there will not be any binding action upon the interposed plate body.

At the inner end of the bearing sleeve 20, the sleeve carries a lateral flange 22 which functions as a spacer for the toothed wheel 23 which is mounted upon the shaft 24. This shaft passes through the bearing sleeve 20 and upon its outer side it has secured thereto the thumb and finger crank which is generally designated 25.

The outer end portion 17a and the portion 17b of the handle 17 lie in the plane of the outer portion 14a of the handle 14. This is clearly shown in Figure 9. Also, the lower edge of the movable handle 17 is shaped to provide the relatively wide flange 26 which lies in a plane transversely to the plane of the body of the handle as shown in Figure 12, whereby a relatively broad surface is provided for contact with the inner sides of the fingers. Thus it will be seen that the portions of the two handles 14 and 17 which are grasped in the hand when the opener is being used, lie in the same plane and are provided at their remote edges with the relatively wide flanges 16 and 26 whereby the handles may be conveniently forced together without danger of having the device turn in the hand and at the same time

a sufficiently wide bearing surface is provided on each handle against which the hand may bear so that the device may be used in comfort.

Disposed against the inner side of the inner portion b of the body plate and secured thereto by the rivets 15 is a cutter carrier plate 27 which is transversely slit along the two parallel lines 28 from the bottom edge of the plate to provide the central portion 28a and the two side wing portions 28b. These side wing portions 28b have the rivets 15 extending therethrough as shown in Figure 3 and accordingly it will be seen that the central portion 28a, being unattached through the major portion of its height, will have a certain degree of resiliency.

Threaded through the free lower end of the portion 28a is the disc cutter support bolt 29 which carries upon its threaded end the lock nut 30 which is positioned in the opening 12 and between the angled portion 14b of the handle 14 and the central portion 28a of the plate 27.

Rotatably supported upon the bolt 29 is the disc cutter 31 which has a relatively long hub 32 whereby good stability is given to the cutter as it rotates upon the bolt.

As shown in Figures 9 and 11 the can rim engaging driving wheel 23 is disposed in a plane between the cutter 31 and the body plate whereby, when the wheel is engaged beneath the can rim 30 and the handles 14 and 17 are forced together, the yoke will shift the wheel toward the cutter and the edge of the cutter will be forced into the head of the can, the wall of the can being interposed between the side of the cutter disc and the inner face of the wheel. Rotary motion may then be imparted to the wheel 23 so as to effect the turning of the can with respect to the cutter disc, by turning the thumb and finger crank 25 in a manner which will be readily obvious.

As shown in Figures 3 and 9 to best advantage, the lower end of each portion 28b has extending therefrom as an integral continuation thereof and in a plane perpendicular to the lower part a of the body plate, a can rim engaging foot 28c. When the device is applied to a can the top edge of the can rim will butt against the under sides of the feet 28c and turn thereagainst. Also, as will be readily apparent, the side of the can below the wheel 23 will rest against the free end of the foot rest 13 whereby, due to the fact that the end of the rest 13 projects inwardly beyond the plane of the inner face of the wheel 23, the device will be maintained on the can at the proper inclination to reduce the frictional engagement 55 of the side of the can against the adjacent face of the driving wheel to a minimum.

The top edge of the plate 27 has a turned flange 33 which extends outwardly across the top edge of the portion b of the body plate and the portion 14b of the handle 14.

The can rest plate 27 is formed of material of sufficient resiliency to permit the lower end of the central portion 28a to be forced inwardly toward the can when necessary, such as when the cutter supported thereon passes the seam of a can.

Figures 4 and 5 illustrate a second embodiment of the invention which is actually merely a modification of the structure shown in Figures 1 to 3 directed to the means by which rotary motion is given to the wheel driving shaft. Accordingly, it is not believed necessary to go into a detailed description of the parts of this modified structure which correspond to or are the same as the parts in the first embodiment.

In the modified construction the body plate

which is designated 34 has formed integral with the forward edge the ear 35. The lower or pivoted handle, designated 36, has formed integral therewith the yoke 37 which is of materially greater length than the yoke 18 and encloses the ear 35 as shown in Figure 5.

The two side portions of the yoke 37, corresponding respectively to the inner and outer portions 17b and 18b, are designated 38 and 39 and passing through these two side portions of the yoke and through the ear 35 is the relatively long pivot pin 40.

The can rim engaging drive wheel supporting shaft is designated 41 and passes through the bearing sleeve 42 which corresponds to the sleeve 20. Upon the outer end of the shaft 41 is secured the relatively large gear 43 by means of which rotary motion is imparted to the shaft 41 and to the can rim engaging driving wheel, not shown.

Numerical 44 designates a pinion gear which is mounted upon the pivot pin 40 and has as an integral part thereof the hub 45 which is positioned between the pinion gear and the side 39 of the yoke 37. Thus the pinion gear, which is of a width considerably greater than the gear 43, is maintained in proper position for toothed connection at all times with the larger gear.

The numeral 45' designates a spacer which is journaled in the opening or bearing of the ear 35 and which is securely riveted by the rivet 40 and maintains the portions corresponding to the portions 17b and 18b in spaced parallel relation to each other so they snugly straddle the lower portion corresponding to portion a.

Inasmuch as the can rim engaging driving wheel, not shown, rotates in the opposite direction to the corresponding wheel 23, the teeth thereof, obviously, would be shaped for such opposite rotation.

The numeral 46 designates a crank arm upon the free outer end of which is pivotally mounted the crank handle 47. The other or mounted end of the crank arm 46 has the outer end of the pinion gear 44 mounted therein as shown in Figure 4 and the ends of the teeth of the pinion gear are swaged as shown by the dotted lines 48 whereby to securely lock the crank and pinion gear together.

It will be readily apparent that in the form of the invention shown in Figures 4 and 5 the handle 26 oscillates on the pivot pin 40 to effect the movement of the can rim engaging driving wheel either toward or away from the cutter. When the device is applied to a can, rotary motion is imparted to the driving wheel through the medium of the crank arm 46 to effect rotation of the gear 43 to which, through the medium of the shaft 41, the can rim engaging driving wheel, not shown, is operatively coupled.

Figures 6, 7, 8 and 10 illustrate another form or embodiment of the invention in which form also the body plate, which is here generally designated 48, is of the same form, as shown in Figure 10, as the body plate 10 in that it has the lower portion a' which is disposed substantially vertically when the device is in position for use, and the obliquely angled upper portion b' which is inclined toward the inner side of the cutter.

The lower portion a' is provided with the vertically extending elliptical opening 49 and the inclined upper portion b' is provided with a notch or recess 50 in its top edge, for the purpose hereinafter described.

The upper or fixed handle, generally designated 51 has the torsionally twisted forward end

portion 52 secured by the rivets 53 to the top side of the inclined portion b', the upper part of the portion 52 covering the outer side of the notch or recess 50.

The numeral 54 designates the thumb and finger crank which is here shown as being of slightly different form from the crank 25 in that it is cut or stamped from a single piece of material and is integrally formed with the stem or shaft 55 which is of polygonal cross section. This shaft passes through and is secured to a journal disk 56 which is located in the elliptical opening or slot 49, as shown in Figure 10, and at the inner side of the disk 56 the shaft passes through and is secured to the journal bearing 57 while upon the inner side of this journal bearing the toothed can rim engaging driving wheel 58 is mounted upon and secured to the shaft 55.

The numeral 59 generally designates the pivoted handle which has the flat forward end portion 60 disposed against the inner side of the body plate 48. This flat portion 60 of the pivoted handle terminates at the forward edge of the body plate and is pivotally coupled thereto by the pivot rivet 61. It will be readily seen that due to the twisted relationship between the rear end of the handle 51 and the forward end portion 52 thereof the two handles 51 and 59 lie in the same plane as to those portions which are grasped in the hands.

The forward end portion 60 of the handle 59 is suitably apertured, as shown in Figure 10, to receive the bearing journal 57 so that the handle 59 may be oscillated about the journal and the shaft 55 while the shaft is being rotated and also while the entire unit making up the shaft, thumb and finger crank, handle 59 and drive wheel 58, is moved in the elliptical slot 49 for effecting the desired relative movement between a can head and the head penetrating knife.

The upper portion b' of the body plate has secured to the inner side thereof the can rest and cutter supporting plate 62 which is secured in position by the rivets 53 which function to secure the top or fixed handle 51 to the body plate. This can rest plate is provided with the spaced slits 63 and the portion of material lying therebetween and forming a central tongue 64, is bent outwardly away from the inner side of the portion b', to a position where it is substantially parallel with the lower portion a' as shown in Figure 10. This tongue 64 provides a resilient support for a straight knife type cutter 65 which is secured against the side of the tongue 64 which is nearest to the body plate, by the screws 66. The knife is thus maintained in a plane which is off-set inwardly from the inner face of the can rim engaging driving wheel 58 as shown in Figure 10 so that when the wheel is engaged beneath a can rim and moved toward the cutter or knife 65, the point of the knife will penetrate the head of the can on the inside of the can rim and the side wall of the can will be disposed between the adjacent faces of the knife and wheel. The resilient character of the metal of which the tongue 64 is formed permits a degree of lateral movement of the tongue and knife so that a thickened portion of the can rim wall as, for example, the seam portion, may readily pass between the knife and wheel.

The end or wing portions 67 of the plate 62, through which portions the rivets 53 pass, have formed integrally with the bottom edges thereof the inwardly directed feet 68 which are substantially perpendicular to the inner side of the
